UNITED STATES PATENT OFFICE

ROBERT MALCOM, OF CHICAGO, ILLINOIS

GOOGLES

Application filed June 10, 1931. Serial No. 543,303.

My invention relates to means whereby the two eye-cups or members of the goggle are adjustably secured together, and at the same time providing for proper ventilation of the interiors of the eye-cups without permitting free entrance of foreign matter or flying metal particles.

That is to say, my invention has for its object the provision of means whereby the connecting member between the two-eye-cups, namely the nose bridge piece, is adjustably secured to each eye-cup, thus enabling the goggle to be readily adjusted to the contour of the wearer's face and to the formation of the nose and its relation to the eyes of the user.

The objects and advantages of the invention will be readily apparent from the detailed description of the accompanying drawing, wherein:—

Figure 1 is a front or outside elevation of a goggle provided with my invention; portions of the head-straps being broken away.

Figure 2 is an enlarged front elevation of portions of the eye-cups, with the lens holding ring and the lens of one eye-cup removed to more clearly disclose the invention, and portions of the other ring and lens broken away.

Figure 3 is a side elevation of one of the eye-cups.

Figure 4 is a transverse sectional view taken substantially on the line 4—4 of Figure 2.

The eye-cups 10, 10, which may have any suitable configuration, are generally cylindrical in shape with the inner or face contacting perimeters shaped to more or less fit the contour of the face about the eyes; and these cups or eye-pieces are usually made of a suitable plastic material, such as bakelite, which, after being properly molded, is baked or hardened.

In goggles of the type in question, the eye-cups are preferably secured together by flexible means; that is to say, the goggle is generally provided with a flexible nose-bridge in the form of a small chain covered with a small piece of rubber tubing. The nose-bridge is generally fixedly secured to the two eye-cups

by means of small staples inserted in the side walls of the eye-cups substantially at the transverse axis of the goggle, with the result that the goggle is not adapted for universal use because of the location of the nose-bridge and the resulting position of the eye-cups relative to the eyes of the wearer.

My invention involves means whereby the nose-bridge is adjustably secured to each eye-cup 10 and in the specific exemplification of the invention the eye-cups 10, 10, on the inner or nose opposing sides, are shown slotted or segmentally cut away at 11 (to any desired extent), see Figure 3, for the purpose of providing openings whereby ventilation of the interior of the eye-cups is obtained and fogging or steaming of the lens is prevented. If desired, the ventilating slot or opening may be omitted.

As these goggles are frequently worn by artisans engaged in working or shaping metal, flying particles of metal and other foreign particles are encountered, thus making it necessary to properly protect or screen the ventilating openings. For that reason I prefer to provide the ventilating slots or openings on the nose opposing sides of the eye-cups where my improved nose-bridge holding means 12 may also constitute a screen or covering for the ventilating openings, as shown in the drawing.

My improved nose-bridge holding means 12 preferably consists of a narrow strip of thin sheet metal or other suitable material and of suitable length to extend beyond the ends of the slot or opening 11 and also permit of a wide range of adjustment of the nose-bridge piece or element 13, so as to adapt the goggle to varying face contours and relations between the nose and eyes.

As the construction of the eye-pieces and the nose-bridge holding means are similar, a description of one eye-piece and holding means will suffice.

The strip of metal, or other suitable material, constituting the holding means 12, is provided with a plurality of slots 14 extending transversely from one longitudinal edge of the strip; the slots 14 preferably flaring or being of slightly increased width at the

longitudinal edge of the strip, as shown in Figure 2.

The strip 12, intermediate of the slotted longitudinal side and the inner ends of the 5 slots 14, is bent substantially at right angles to the other longitudinal side or unslotted portion 15 of the strip, as more clearly shown in Figures 3 and 4.

The opposite ends of the unslotted portion 10 15 of the strip are bent backwardly toward the slotted longitudinal side and thence laterally to provide the attaching ears or ends 16, 16, whereby the nose-bridge holding means are securely fastened to the side walls 15 of the eye-cups, as for example by suitable eyelets, as shown in Figure 3 at 17.

By bending the ends of the strip backwardly and thence outwardly as shown, the main portion of the strip will be held in slight 20 spaced relation with the side wall of the eye-cup and hence not only afford greater ventilation but also providing a socket or pocket on the inner side of the means to receive the ends of the nose-bridge piece 13, as shown at 25 18 in Figure 4.

The width of the strip and the position of the ends 16 are such that the means may be located on the side walls of the eye-cups intermediate of the lens holding bezel or flanged 30 ring 19 and the slightly flared or enlarged inner face engaging perimeter of the eye-cup.

In goggles of the character here in question, the lenses are usually removably held in place against the outer perimeters of the 35 eye-cups by means of flanged rings internally threaded to screw onto the exteriorly threaded portion 20 of the eye-cup and for that reason the holding means 12 is shown constructed and arranged as described; the 40 holding means 12 being arranged to extend partially about the eye-cups from a point preferably slightly beneath the transverse axis of the goggle, as shown in Figure 2, as location of the nose-bridge any great extent 45 beneath the horizontal or transverse axis of the eye-pieces would not be likely nor practicable.

The eye-pieces of goggles of this type are 50 preferably secured together by a flexible nose-piece; and this nose piece 13 in the particular exemplification of my invention is in the nature of a chain consisting of a plurality of hard spherical portions or metallic balls 21, threaded onto a suitable wire or cord so as 55 to permit a slight spacing of the balls 21 at opposite ends of the chain and hence provide small sockets or interstices particularly at the ends of the nose piece.

In view of the fact that the connecting 60 strand or element of the nose-bridge is intended to be slipped into the desired slot in the holding means 12, I prefer to unit the enlarged portions or spherical members 21 by small metallic link elements 22, see Figure 4, 65 whose ends are disposed through small holes

in the opposite sides of the spherical members 21 and the ends enlarged to prevent withdrawal.

In order to properly protect the nose of the wearer and prevent metal contact, the nose-bridge is shown provided with a piece of small rubber tubing 23.

As is apparent from the construction shown, the ends of the nose-bridge or chain may be arranged in any one of the slots 14 75 of the holding members 12 in keeping with the wishes or needs of the wearer; and as the spherical or spaced enlarged portions of the nose-bridge are larger than the widths of the slots, lateral withdrawal of the nose piece 80 is impossible.

As the open ends of the slots 14 are disposed laterally toward the walls of the eye-cups and are located adjacent to the normal position of the bezels or lens holding rings 19, 85 it will be seen that the ring 19 will be disposed across the slotted longitudinal edge of the strips 12 and thus prevent withdrawal of the ends of the nose-piece from the slots 14; that is to say, the open ends of the slots 14 90 will be disposed at the lower sides or inner perimeters of the rings and closed thereby.

In order to assemble and adjust the nose-bridge, the lens holding ring 19 must first be removed and the end of the nose-bridge 95 13 inserted in the selected slot 14 which will provide the proper positioning of the eye-cups relative to the eyes of the wearer. The end of the nose-bridge is slipped through the open end of the slot and moved to the 100 closed end of the slot located in the vertical leg or side 15 of the holding strip 12, as shown in Figure 4; after which the lens holding bezel or ring is then screwed into place. It is apparent that a wide range of 105 adjustments is provided between the upper and the lower ends of the holding strips 12, as viewed in Figures 1 and 2.

Aside from the adjustment of the nose-bridge relative to the transverse or horizontal axis of the goggle, as just mentioned, the nose-bridge 13 may also be adjusted so as 110 to vary the distance between the two eye-cups so as to adapt the goggle to closely set or widely set eyes; such adjustments being obtained by either shortening or lengthening the portion of the nose-bridge between the eye-cups. That is to say, the extreme end portions or spherical members 21, or a number of such members 21 may be 115 arranged within the socket or pocket 18 formed by the holding strip 12, as shown in Figure 4. As is apparent therefore, my improved means permits of a double adjustment to be made, while at the same time permitting circulation of air through the slots 14 into the eye-cup interior.

For purposes of exemplification, I have shown the nose piece in the form of small spherical members or balls flexibly secured 125 130

together so as to provide interstices or spacing between the spherical members, but it is apparent that this nose piece may be differently formed to permit the ends to be readily inserted in the slots or openings and effect gripping relation; and it is also apparent that a goggle with the different type of lens-holding means may be employed; the drawing illustrating a simple embodiment of my invention which I have described in terms employed merely as terms of description and not as terms of limitation.

What I claim is:

1. In a goggle of the character described, the eye-cups whereof are provided with removable lens holding rings, a detachable nose-bridge provided with transversely disposed interstices spaced apart lengthwise of the nose-bridge, and means disposed circumferentially on the nose sides of the eye-cups and provided with transversely disposed spaced apart slots open at one side of said means, said slots being adapted to match the interstices in the nose-bridge and the open ends of the slots being disposed toward the eye-cups into proximity of the lower side of the lens holding rings, whereby passage of the attached end of the nose-bridge through said open ends of the slots is prevented when the rings are on the eye-cups in lens holding position.
2. A goggle comprising a pair of eye-cups, the side walls on the nose side being provided with air admitting openings; a cover member for the openings in each eye-cup wall disposed

are secured to the eye-cup walls; and a chain for connecting the eye-cups, each alternate link whereof is enlarged while the intermediate links are adapted to slip through the ends of the slots in said strips, whereby said chain is adjustably secured to the eye-cups.

4. In a goggle of the character described having eye-cups provided with removable lens holding rings adapted to fit about the outer ends of the eye-cups, the eye-cup walls on the nose sides being provided with segmental upstanding portions arranged in spaced relation with the side walls of the eye-cups, said portions being provided with a plurality of open ended slots arranged transversely and spaced apart lengthwise of the segmental portions with the open ends disposed toward the ring receiving portions of the cup side walls and to be closed by the rings when the latter are in place, and a separate nose-bridge provided with transverse interstices adapted to match the slots in said segmental portions while the other portions of the nose-bridge are larger than said slots, whereby removal of the nose-bridge is impossible while the lens holding rings are in place.

5. A goggle comprising a pair of eye-cups, lens holding rings arranged to screw onto the side walls of the cups, a nose-bridge holding member secured on the nose side of each cup wall and disposed in a circumferential direction and comprising an elongated strip bent longitudinally into angular form with one longitudinal side disposed substantially par-

of each strip having air admitting openings, and a flexible nose piece consisting of a plurality of beads secured together by links adapted to slide into said slots while the end 5 beads are adapted to be positioned beneath the upper side of the strip, the open ends of the slots in the upper sides of said strips being adapted to be lapped by the lens holding rings when the latter are in lens holding position.
